UNITED STATES PATENT OFFICE.

SHERWOOD C. BLISS, OF BAYONNE, NEW JERSEY.

ATTACHMENT FOR LATHES.

1,401,954.

Specification of Letters Patent. Patented Jan. 3, 1922.

Application filed November 20, 1918. Serial No. 263,303.

To all whom it may concern:

Be it known that I, SHERWOOD C. BLISS, a citizen of the United States, and a resident of Bayonne, in the county of Hudson and State of New Jersey, have invented certain new and useful Improvements in Attachments for Lathes, of which the following is a specification.

The invention relates to an attachment for lathes, whereby the same may be employed for chasing the interrupted threads on gun breech plugs and screw box liners, as well as for accurately relieving or backing off the teeth of taps, cutters, hobs, mills, etc., said attachment being adapted to be used with lathes of standard type already in service or to be originally built in with same.

It has for its object to accomplish a rapid and accurately controlled movement of an external or internal thread chasing or other tool, and to effect same with a minimum of shock in that the novel construction permits of a greatly reduced weight of the parts, it being understood that the control is effected by means of a cam which, in accordance with the present invention, is not of the usual peripheral type employed for this work but is a face cam. It will be appreciated that in apparatus of this character the accuracy of the work required precludes the use of any cushioning device for absorbing the shock resulting from stopping of the rapidly moving tool slide in the proper position for chasing or relieving, and that the lack of any such cushioning device imposes heavy stresses in parts of the mechanism. Moreover, the time available for the movement from one radius of operation to another is so short that the movement required must be

very rapid. A further object of the invention consists in providing a cam whose controlling surfaces may be readily machined to very accurate dimensions, and in so mounting the back face of the cam as to eliminate all bending strains of same and its carrying shaft, and to make possible the ready renewal of all surfaces subject to shock. This is attained by providing a large bearing area, not possible with the peripheral cams heretofore employed wherein contact in the action is substantially along a line and causes rapid wear. This latter action resulting in undue wear, and the fact that heavy parts are necessary and cause heavy shock due to impact of the said parts, are par-

ticularly objectionable features of the apparatus as heretofore employed.

The nature of the invention will be best understood when described in connection with the accompanying drawings, illustrating the invention embodied in a device for chasing interrupted threads on gun breech plugs, and in which—

Fig. 1 is a front elevation of the active portion of a lathe with said device adapted thereto.

Fig. 2 is a plan thereof.

Fig. 3 is a section taken on the line 3—3, Fig. 2 looking in the direction of the arrows.

Fig. 4 is a fragmentary transverse section taken on the line 4—4, Fig. 3.

Fig. 5 is a diagrammatic view, illustrating the action of the device.

Fig. 6 is an end view of a breech plug.

Similar characters of reference designate corresponding parts throughout the several views.

Referring to the drawings, 10 designates the lathe bed upon which there is caused to travel, either automatically or manually, the usual carriage 11 provided with a cross-slide 12. Along the lathe, preferably at the back thereof, is mounted an actuating shaft 15 which is designed to be rotated in any suitable manner from the head-stock spindle 16 of the lathe, as for example through intermediate gears 17. Between the head-stock spindle 16 and the tail-stock spindle 16' is secured the work 18 which, in the present instance, is illustrated as a gun breech plug, and the same is driven from the face plate 19 through a driver 20, all of which is well understood and forms no particular part of the invention.

Mounted upon the carriage 11, and driven from the shaft 15 through bevel gears 25, is a cam shaft 26 through whose rotation the controlling movement for the operations hereinafter referred to is obtained. To this end, the shaft 26 extends into the cross-slide 12; that is to say, a flanged sleeve 27, keyed to said shaft, is caused to rotate within a bushing 28 of the said cross feed slide. The bushing 28 is provided with an outward flange 29 between which and the flange 30 of the sleeve 27 is mounted a face cam 31, the back of which cam abuts the flange 29 and is freely rotatable with respect thereto. The cam is secured to and carried by the flange 30 so as to rotate, through sleeve 27, with

the cam shaft 26. In this manner, the cam is caused to partake of the motion of the cam shaft 26, and at the same time allows of the cross feed of the slide 12 relatively to 5 said cam shaft.

The slide 12 carries at its upper portion the tool slide 35 which is made adjustable at right angles to the motion of the cross slide 12 in a manner well understood. The tool 10 slide carries a suitable tool 36 designed to coact with the work 18, as the latter is rotated. In addition to its longitudinal feed, and cross feed movement through slide 12, the tool slide 35 is caused to be rapidly and 15 accurately reciprocated toward and away from the work 18 in accordance with the design of the cam 31 whose face is formed to suit the character of the work in hand. This is effected by providing the said slide 20 35 at its under surface with a cam block 37 engaging the face of cam 31 to thereby control the in-and-out position of the slide 35 and its tool 36, through the rotation of the cam and in accordance with the position of 25 the work. As is herein shown, the cam acts to force the tool 36 toward the work 18, and is returned by resilient means, the slide 35, for this purpose, having an outward tubular extension 38 into which projects a rod 39 30 adjustably secured through nuts 40 to a bracket 41 extending upwardly from slide 12. Between the head 42 of said tubular extension and the inner end of rod 39, which is provided with a head or piston 43, is a coil 35 spring 44 acting to draw the tool slide toward said bracket and thus, when the cam relieves the cam block, the latter will be drawn outwardly to continually maintain contact between its face and that of the cam. 40 I claim:

1. In apparatus of the character set forth: a suitably driven cam shaft, a sleeve about same and driven thereby, a cross slide provided with a bearing for rotatably 45 mounting said sleeve, a face cam rotated by said sleeve and bearing at its back surface

against said cross slide, and a tool slide moved by said cam and carried by said cross slide.

2. In apparatus of the character set forth: a suitably driven cam shaft, a flanged sleeve about same and driven thereby, a cross feed slide, a bushing mounted within said slide about said cam sleeve and within which the latter is adapted to rotate, said bushing being provided with a flange at its outer end, and a face cam retained between the flange of said bushing and the flange of said cam sleeve and driven by said sleeve. 55

3. In apparatus of the character set forth: a suitably driven cam shaft, a flanged sleeve about same and driven thereby, a cross feed slide, a bushing mounted within said slide about said cam sleeve and within which the latter is adapted to rotate, said bushing being provided with a flange at its outer end, and a face cam retained between the flange of said bushing and the flange of 60 said cam sleeve, bearing against the flange of the former and carried by the flange of 65 the latter to rotate with the cam sleeve. 70

4. In apparatus of the character set forth: a suitably driven cam shaft, a face cam rotated thereby, a cross feed slide within which said cam shaft is rotatably mounted, a tool 75 slide carried by said cross feed slide, a cam block carried by said tool slide and actuated by said face cam to move the said tool slide in one direction, a bracket secured to the cross feed slide, a tubular member carried by 80 said tool slide, having a rod extending therein from said bracket, and a coil spring mounted about said rod within said tubular member, one end thereof bearing against an end of said rod and the other against an end 85 of said tubular member to draw the tool slide toward said bracket.

Signed at Bayonne, in the county of Hudson and State of New Jersey this 16th day of November, A. D. 1918.

SHERWOOD C. BLISS.
